CLAIM

The ornamental design for a hair braiding tool, as shown and described.

DESCRIPTION

FIG. 1 is a front view of the hair braiding tool showing the new design, the rear view being a mirror image thereof; FIG. 2 is a top view of FIG. 1, the bottom view being a mirror image thereof; FIG. 3 is a right side view of FIG. 1; FIG. 4 is a left side view of FIG. 1; FIG. 5 is a first alternate configuration view of FIG. 1; FIG. 6 is a second alternate configuration view of FIG. 1; and, FIG. 7 is a reference view of usage of FIG. 1. The broken lines in FIG. 7 depict unclaimed environment which forms no part of the claimed design.
